UNITED STATES PATENT OFFICE.

CHARLES F. WINSLOW, OF PAWTUCKET, RHODE ISLAND.

PLIERS.

SPECIFICATION forming part of Letters Patent No. 289,052, dated November 27, 1883.

Application filed May 26, 1883. (No model.)

To all whom it may concern:

Be it known that I, CHARLES F. WINSLOW, of Pawtucket, Providence county, Rhode Island, have invented certain new and useful 5 Improvements in Pliers and Nippers, of which the following is a specification, reference being had to the drawings accompanying the same, making part hereof.

The object of this invention is to furnish 10 pliers and nippers of such construction that their holding-jaws shall remain constantly parallel, although opened and closed by crossing pivoted levers. To accomplish this object I make one jaw integral with one of the levers, 15 slot, or groove, the stock adjacent to said jaw to receive the shortened transverse shank of the other jaw, which shank has a straight rack upon it engaging with a segment-gear formed on the end of the other lever, with the 20 connecting-pivot as a center. This latter lever is shorter than the other one by as much as the length of its jaw and the breadth of the transverse shank. This shank is shaped in cross-section to fit the groove or slot through 25 the stock of the other jaw, so as to provide for a free movement and yet hold the jaws parallel.

The drawings show in Figure 1 a plan view 30 of my improved pliers, the dotted lines denoting the position when spread, and showing the parallelism of the holding-jaws. Fig. 2 is an edge view. Figs. 3 and 4 show the longer lever in plan and edge view, while Figs. 5 and 6 are similar views of the shorter lever; 35 and Figs. 7 and 8 are similar representations of the detached jaw and its transverse shank, worked by the terminal segment-gear on the shorter lever.

A is the longer lever, and B the shorter one, united by the pivot C. The lever A is slotted 40 (as at *a*, Fig. 4) from the base of the holding-jaw A' to and beyond the pivot C, in order to receive and permit motion of the reduced part *b* of the shorter arm and the transverse shank *d* of the detached jaw D. The lever A, slotted 45 stock or body, and jaw A' are continuous or integral. The part *b* of the lever B terminates in a segment-gear, *g*, which engages with the 50 teeth of a straight rack, *h*, formed on the edge of the transverse shank *d*, and hence the movement of the levers A and B on their pivot C causes the jaw D to move toward and from the jaw A'. This movement is in a right line, since the shank *d* is grooved lengthwise to fit 55 corresponding ribs within the recess or slot *a*.

I am aware that in various tools—such as vises, wrenches, and the like—a parallel movement has been attained by various means; hence I do not claim such movements, broadly, nor as applied to tools generally; but 60

What I claim as my invention in pliers and nippers, and desire to secure by Letters Patent, is—

The improved pliers or nippers herein described, consisting of the jaw A' and lever A, 65 formed integral and slotted at *a*, in combination with the lever B *b*, pivoted thereto at C, the part *b* terminating in a segment-gear working in the slot *a* in engagement with a rack on the edge of the grooved transverse shank *d* of 70 the jaw D, substantially as and for the purpose set forth.

CHAS. FREDERIC WINSLOW.
